UNITED STATES PATENT OFFICE.

ALONZO WARREN, OF BOSTON, MASSACHUSETTS.

SEWING-MACHINE TRIMMER.

SPECIFICATION forming part of Letters Patent No. 278,300, dated May 22, 1883.

Application filed February 9, 1883. (No model.)

To all whom it may concern:

Be it known that I, ALONZO WARREN, of Boston, in the county of Suffolk and State of Massachusetts, have invented certain Improvements in Sewing-Machine Trimmers, of which the following is a specification.

This invention has for its object to provide an improved attachment for sewing-machines for the purpose of trimming loosely-woven or knit fabrics while the same are being stitched, and in a line parallel with the stitching.

My invention consists in two co-operating cutting or shearing blades arranged and operating, as hereinafter described, to alternately clear and enter the throat-plate of the machine, and to gather a portion of the work and cut it in a substantially vertical direction, one of said blades moving in such direction that it constitutes a helper or auxiliary for the feeding devices of the machine.

The invention also consists in the form and arrangement of the cutting-edges, whereby the cutting action is caused to commence at or near the points of the blades and progress gradually to their inner ends, all of which I will now proceed to describe.

Of the accompanying drawings, forming a part of this specification, Figure 1 represents a perspective view of a portion of a sewing-machine provided with my improvement. Figs. 2 and 3 represent elevations of my improved attachment in different positions. Fig. 4 represents an enlarged view, showing the cutters in the act of grasping the material.

The same letters of reference indicate the same parts in all the figures.

In carrying out my invention I secure to any suitable part of the overhanging arm or goose-neck A of a sewing-machine a depending standard, a, to which I pivot, at b, a blade, c, having its cutting-edge c' formed on a re-entrant curve and terminating in a sharp point adapted to easily penetrate a loose textile fabric, such as hosiery or material of like texture. The blade c is adapted to oscillate on its pivot in a substantially vertical plane, and is placed in such relation to the throat-plate or bed of the machine that when pressed downwardly from the position shown in Fig. 2 its point will penetrate the work on said plate or bed and enter a slot therein.

d represents a co-operating blade pivoted at

e to the blade c, and having a cutting-edge, d', which is nearly vertical, but preferably has a slight re-entrant curve, and is in rubbing contact with the cutting-edge c'. The shank d' of the blade d is extended upwardly, and is adapted to be operated by a moving part of the machine, so that when the machine is in operation the blade d will be reciprocated vertically. In the present instance the shank d' is pressed upwardly a suitable distance by a spring, f, and is arranged so that the oscillating lever g, in moving downwardly, will strike and depress said shank. Any other suitable means for reciprocating the blade d may be employed without departing from the spirit of my invention. It will be seen that when the blade d is vertically reciprocated it oscillates the blade c on its pivot. When the blade d moves downwardly the point of the blade c penetrates the work and its cutting-edge moves crosswise of the cutting-edge of the blade d, so as to cut the material interposed. The curvature of said cutting-edges is such that their points meet first after the point of the blade c has penetrated the material, a portion of the material being thus gathered or compressed between the two blades and cut by a gradual upward progress of the cutting action, or, in other words, of the point of contact of the two blades from their outer to their inner ends, the most of the cutting being performed at the upper portions of the cutting-edges, or near the pivot e, that connects the two blades, so that the material will have less tendency to spring the blades apart than in ordinary shear-blades, in which the cutting action commences near the pivot and progresses away therefrom. The blades c d are so arranged relatively to the needle that when said blades descend, the blade d will enter the cut made by the preceding stroke, while the blade c will penetrate the material at a point in advance of the end of said cut, the two blades co-operating in severing the interposed or gathered portion of the material, and thus extending the cut to the point penetrated by the blade c. Both blades in operation are alternately raised above the throat-plate of the machine, so that the latter is clear and the work can be moved freely thereon, and depressed so as to enter a slot in said throat-plate, the cutting being performed during the downward movement. The

pivot *b* of the blade *c* is so located that when said blade is swung downwardly to penetrate the work it will also move to some extent in the same direction that the work is fed. Although in the machine illustrated in the drawings this movement of the blade *c* occurs after the needle has penetrated the work, and the feed has ceased to operate, said movement in effect helps the feed by preventing any pressure on the work in the opposite direction to that in which the work is moved by the feed. In all shears heretofore there has been a tendency to crowd the work backwardly or in a direction opposite to that in which the work is fed, this tendency increasing as the shears become dull. The work therefore sometimes yields or slips before the shears, and is bunched up or displaced backwardly by the action of the shears, so that when the needle rises the work will creep backwardly over the feed-dog to some extent and partially neutralize the feeding action of the latter. Such a result cannot be produced by the operation of my improved blades. It is obvious that the descent of the needle may be differently timed, so that the described movement of the blade *c* will occur wholly or in part before the needle has penetrated the work, and while the latter is being moved by the feed-dog. In such case the blade *c* will act directly to help the feed. The two features above described—viz., rising and falling movement of the two blades, the progress of the cutting action from the points toward the pivot of the cutting-blades, and the feed-helping action of the blade *c*—distinguish my invention from all cutting attachments heretofore employed having two moving shear-blades. Heretofore in such cutting attachments the blades have been so formed and arranged that the cutting action has progressed outwardly from the pivot to the points of the blades, as in ordinary shears, and in a direction opposite to the direction of the feed. The work therefore has a tendency to spring the blades apart and cause them to cut imperfectly, and the blades in approaching each other have a tendency to press the work backwardly, this latter tendency being greater when the cutting-edges are dull. These objections are entirely obviated by my invention.

I do not limit myself to the particular form and arrangement of the blades *c d* shown and described, as the same may be variously modified without departing from the spirit of my invention.

55

I claim—

1. A trimming attachment for sewing-machines, composed of two co-operating shear-blades adapted to rise and fall, so as to alternately clear and enter the throat-plate, and to cut the material during their downward movements, as set forth.

60

2. A trimming attachment for sewing-machines, composed of two co-operating shear-blades adapted to rise and fall, so as to alternately clear and enter the throat-plate and to cut the material during their downward movement, one of said blades having a substantially vertical movement and the other a movement in the direction of the feed, as set forth.

65

3. A trimming attachment for sewing-machines, composed of a piercing and cutting blade adapted to oscillate in a substantially vertical plane, and a reciprocating blade pivoted to said oscillating blade and imparting motion thereto, said blades being formed at their cutting-edges, substantially as described, to gather and cut a portion of the material at each downward movement and prevent the work from pressing backwardly against the feed, as set forth.

70

4. A trimming attachment for sewing-machines, composed of a piercing and cutting blade adapted to oscillate in a substantially vertical plane, and a reciprocating blade pivoted to said oscillating blade and imparting motion thereto, said blades being formed and arranged, substantially as described, to gather the material at their points and cut the same by a progress of the cutting action of the blades from the outer to the inner ends thereof, as set forth.

75

In testimony whereof I have signed my name to this specification, in the presence of two subscribing witnesses, this 7th day of February, 1883.
